COMBINED BOTTLE AND STOPPER

Marie Joseph Coffy, Paris, France, assignor to Saint-Gobain-Desjonquieres, Levallois-Perret, France

Filed Jan. 30, 1975, Ser. No. 545,701

Claims priority, application France Sept. 24, 1974

Term of patent 3½ years

Int. Cl. D9—01

U.S. Cl. D9—118

FIG. 1FIG. 2*FIG. 4*FIG. 5*FIG. 3FIG. 1 is a side elevational view of a combined bottle and stopper embodying my new design;

FIG. 2 is a side elevational view of the bottle;

FIG. 3 is a bottom plan view of the bottle;

FIG. 4 is a side elevational view of the stopper; and

FIG. 5 is a top plan view of the stopper.

The side opposite that seen in FIG. 1 is the same in appearance as the side shown.

I claim:

The ornamental design for a combined bottle and stopper, substantially as shown and described.
